WITNESS:

UNITED STATES PATENT OFFICE.

THOMAS F. LAWTER AND ALVA H. LAWTER, OF NEWCASTLE, INDIANA.

COMBUSTION-PROMOTING DEVICE.

Application filed September 6, 1922. Serial No. 586,466.

To all whom it may concern:

Be it known that we, THOMAS F. LAWTER and ALVA H. LAWTER, citizens of the United States, residing at Newcastle, in the county of Henry and State of Indiana, have invented new and useful Improvements in Combustion-Promoting Devices, of which the following is a specification.

Our present invention has reference to a heating plant.

Our object is to provide in a stove or furnace a means for admitting air into the fire box thereof, causing such air to be heated and the heated air delivered downwardly on to the burning coals to mix with the gases therefrom, and thereby greatly promoting combustion, and consequently obtain a greater heat with a smaller consumption of fuel.

The foregoing, and other objects which will present themselves as the nature of the invention is better understood, may be accomplished by a construction, combination and operative association of parts, such as is disclosed by the drawings which accompany and which form part of this specification.

In the drawings:—

Figure 1 is an approximately central vertical longitudinal sectional view through a heating plant, such as an ordinary furnace, provided with the improvement.

Figure 2 is a sectional view on the line 2—2 of Figure 1.

Referring now to the drawings in detail, the numeral 1 designates a heating plant, such as an ordinary furnace. In the furnace, and extending centrally from but secured a slight and suitable distance above the grate 2 there is a drum 3. The drum is gradually flared inwardly from its lower open end to its top, the open end of the said drum being so positioned that air from the ash pit will enter the drum. The open end of the drum may be provided with outwardly directed ears 4 which are secured in any desired manner in the furnace for supporting the same. The drum 3, at its reduced upper end is provided with a tubular extension 5, and on this extension there is formed a hollow head 6. The head 6 is in

the nature of an air mixer and the walls constituting the same are concavo-convex in cross section, the upper and lower walls being connected by a rounded wall or edge 7, and the said wall or edge is provided with spaced apertures 8 whereby heated air from the mixing chamber or head 6 will be delivered downwardly on to the burning coals.

Connected to the drum preferably at the juncture of the pipe or tubular extension 5 with the conical end thereof, there is a cold air inlet pipe 10, the said pipe extending through one of the sides of the furnace and if desired, this pipe may communicate with the outer atmospheric air.

It is thought that the foregoing description, when taken in connection with the drawings will fully set forth the construction, operation and advantages of the improvement to those skilled in the art to which such inventions relate, it being apparent that the live coals will effectively heat the drum and the elements associated therewith, that cool air will enter the drum through the pipe 10, that the said air will circulate through the pipe extension 5 into the mixing chamber 6 and will be from thence delivered through the restricted apertures in the head or mixing chamber downwardly on to the live coals, thereby materially increasing combustion and also thereby obtaining a greater amount of heat from a less consumption of fuel.

Having described the invention, we claim:

The combination with a heating device, of a flared drum having its widened end open and arranged above the grate of the heating device, said drum having at its restricted end a tubular extension which terminates in a hollow head, the opposed walls of the head being rounded from the center thereof downwardly and being connected by a rounded edge which is apertured on the under face thereof and a cold air conducting pipe extending through the heating device and connected to the tubular extension.

In testimony whereof we affix our signatures.

THOMAS F. LAWTER.
ALVA H. LAWTER.
